A. J. KERSHNER
INVENTOR

BY *Victor J. Evans*

ATTORNEY

WITNESS:

UNITED STATES PATENT OFFICE.

ANDREW J. KERSHNER, OF CHICAGO, ILLINOIS.

WRENCH.

Application filed February 16, 1923. Serial No. 619,475.

To all whom it may concern:

Be it known that I, ANDREW J. KERSHNER, a citizen of the United States, residing at Chicago, in the county of Cook and State of Illinois, have invented new and useful Improvements in Wrenches, of which the following is a specification.

This invention relates to wrenches, and an object of the invention is to provide a solid substantial wrench structure of the vise type, which embodies a relatively large body having a rigid jaw at one end thereof, along which body a movable jaw is mounted, the said movable jaw being adjustable by rotation of a handle which is in turn carried by a suitable carrying structure pivotally connected to the rigid jaw carrying body.

Other objects of the invention will appear in the following detailed description taken 20 in connection with the accompanying drawings wherein:—

Fig. 1 is a top plan of the improved wrench.

Fig. 2 is a longitudinal section through 25 the wrench taken on the line 2—2 of Fig. 1.

Fig. 3 is a cross section taken on the line 3—3 of Fig. 1.

Fig. 4 is a cross section on the line 4—4 of Fig. 1.

Referring more particularly to the drawings, the improved wrench comprises a body 1 which is substantially U shaped and has a jaw or wrench face 2 formed on the inner edge of its bight portion. The legs 3 of the body 1 are provided with longitudinal slots 4 which serve as guideways for the ribs 5 formed on the edges of the movable block 6. The block 6 has a wrench jaw 7 formed thereon which cooperates with the wrench face or jaw 2. The substantially U shaped body 1 is attached, by means of rivets or suitable pins 8 to a block 9, to which block a handle structure 10 is pivotally connected by means of the bolt 11 so as to assume limited angular positions for allowing

the wrench to be used in various positions. A feed screw 12 is connected to the slidable block 6 as shown at 13 and it threadably engages through the stationary block 9. The end of the feed screw 12 remote from the slidable block 6 is forked as shown at 14 and has an operating handle 15 pivotally connected thereto. The operating handle 15 is rotatably carried by the handle structure 10 and it has a hand wheel 16 on its outer end 55 by means of which the handle 15 may be rotated for adjusting the jaw 7 relative to the jaw 2.

It is, of course, to be understood that the invention may be constructed in other manners and the parts associated in different relations and, therefore, I do not desire to be limited in any manner except as set forth in the claims hereunto appended.

Having thus described my invention what I claim is:—

1. In a wrench, a substantially U shaped body having a wrench jaw on the inner edge of its bight portion, a block slidably carried by the legs of said body, a wrench jaw carried by said block, a block rigidly attached to said body, a handle structure pivotally carried by said rigid block, and means carried by said handle structure and rigid block and connected to said slidable block 75 for adjusting the position of the jaw carried thereby.

2. A wrench, comprising a body having a wrench jaw thereon, a block slidably carried by said body, a wrench jaw carried by 80 said block for adjustment relative to the first named wrench jaw, a block rigidly carried by said body, a handle pivotally carried by said rigid block, a feed screw adjustable through said rigid block, and an operating 85 rod carried by said pivotal handle and connected to said feed screw.

In testimony whereof I affix my signature.

ANDREW J. KERSHNER.
